UNITED STATES PATENT OFFICE.

CHARLES KAESTNER, OF CHICAGO, ILLINOIS.

BREWER'S MASHING-MACHINE.

SPECIFICATION forming part of Letters Patent No. 479,189, dated July 19, 1892.

Application filed April 2, 1891. Serial No. 387,337. (No model.)

To all whom it may concern.

Be it known that I, CHARLES KAESTNER, a citizen of the United States, residing at Chicago, Illinois, have invented certain new and useful Improvements in Brewers' Mashing-Machines, of which the following is a specification.

My invention relates to that class of brewers' mashing-machines wherein the vertical power-shaft which carries the mash-working devices—such as rakes and scrapers—is made endwise movable, so that the rakes or scrapers may be elevated above the mash; and my invention relates more particularly to a mashing-machine of the class described wherein the vertical shaft to which the mash-working appliances are connected is made in two sections, one of which is rotatable and the other fixed. The fixed section has a step, in which the lower end of the rotatable section is seated, and I have provided convenient and simple devices for elevating and lowering the shaft. In the preferred construction I make the lower shaft-section hollow and employ a screw, which works through a nut fixed in the lower end of the hollow shaft, and this screw I turn by means of any suitable gearing, manipulated either by hand or by power, to raise the shaft. In another form of construction the screw projects through a nut formed in the hub of a gear-wheel placed below the shaft; but of course in this construction there must be a clear space below the foundation on which the machine rests to permit the screw to extend below the hanger or foundation when the shaft is lowered in position for mashing. I have also provided a divided clamping-ring to hold the shaft-sections together and a divided coupling for connecting the driving-gear for the screw and its support, and to this coupling I secure a hanger for a driving-shaft, and thus adapt said support to be swung in any direction. I have also provided ball-bearings for the hub of the driving-gear which turns the central shaft and for the hub of the driving-gear which turns the screw. I have also provided means for counterbalancing the weight of the machine, said means comprising a hub secured with the shaft and having guide-arms to steady the shaft and studs carrying sheaves,

around which the counterbalance-cables are passed.

In the accompanying drawings, Figure 1 is an elevation sectional through the mashing-tub, showing the shaft lifted to elevate the mash-working devices. Fig. 2 is a detail of the lower end of the non-rotating shaft-section and showing the screw threaded through the hub of the driving-gear and showing, also, a ball-bearing for said hub and the divided hanger. Fig. 3 is an elevation, partly in section, of the lower end of the rotatable section of the shaft and showing the fixed section hollow and with a screw working through a nut in the lower end of the shaft up into its hollow. Fig. 4 is a detail view of the nut, shaft, and screw and showing, also, in section the hub of a guide carrying the counterbalance-sheaves. Fig. 5 is a plan view of the hanger. Fig. 6 is a plan view of the guide and sheave supports. Fig. 7 is a detail view of a stuffing-box, and Fig. 8 is a detail view of a ball-bearing for the upper driving-gear. Fig. 9 is a plan view of the parts shown in Fig. 3 above the break in the latter view.

In the drawings, 6 indicates the mash-tub. In the bottom of the tub is a stuffing-box 7, (see Fig. 7,) through which may be adjusted vertically the non-rotating shaft-section 8. The upper end of said shaft-section is fitted with a step, as shown particularly in Fig. 3, and in this step is seated the rotatable shaft-section 9, to which are secured the bearings 10 and 11 for the inner ends of the scraper-shaft 12 and the rake-shaft 13, respectively, the outer ends of these shafts being supported by the hangers 14 and 15 from the beam 16, which is also secured to the rotating shaft-section 9. Gearings is applied to said shaft-section above the top of the mash-tub for rotating it, and its rotation causes the rake and scraper shafts to sweep around the tub. The rake-shaft is rotated on its own axis by means of the bevelled pinions 17 and 18, the former being secured with its shaft and the latter being secured with the shaft-section 8. The bearing 11, which is rigidly secured to the shaft-section 9, is held by means of the divided collar 19, one edge of which fits into a groove 20 in the bearing 11 and the outer rim of which is bolted to the arms of the gear 18. This di-

vided collar serves as a coupling to hold the shaft-section 9 to the section 8 while lowering the machine and permits of the two being readily connected or separated at will.

5 In the construction shown in Figs. 1 and 2 a screw 21 has its upper end fastened in a bushing 22, and the latter is secured by the tap-bolts 23 to the lower end of the shaft-section 8. This screw has a threaded engagement with the hub of the gear 24, which is driven by a pinion 25 on a shaft 26. The inner end of said shaft is supported from the gear 24 by means of the divided hanger 27. (Shown in Fig. 5.) The hub of the gear 24 travels upon the balls 28, which are confined in grooves formed in the lower face of the hub and in the upper face of the bearing or support 29, which is coupled with the hub by means of the hanger 27. This hanger permits the shaft 26 to be swung in any direction and forms a coupling for the bearing.

In the construction shown in Fig. 3 the screw 21 is secured with the gear 24 by means of the set-screw 21^a, and the threaded end of the screw 21 projects into the hollow of the shaft-section 8, in the lower end of which is fitted the bushing 22, which in this instance is threaded. The advantage of this construction is that the screw passes into the hollow of the shaft-section, and it therefore requires less space below the machine.

The shaft 26 may be rotated in any convenient manner—as, for example, by the hand-wheel and driving-chain shown in Fig. 1 or by a belt or other suitable power. It is obvious that the rotation of this shaft, acting through the gear 24, will with either of the constructions described enable the vertical adjustment of the shaft-sections 8 9, thus raising or lowering the scrapers and rakes or other mash-working devices.

In the operation of mashing it is frequently desirable to elevate the scrapers and rakes to the top of the mash, so as to break up the hard crust which forms after the wort is drawn off, and in discharging the grains the scrapers and rakes are usually lowered gradually, so as to facilitate the operation of clearing the tub. In order to render the adjustment easy, I have provided a counterbalance-weight 30, suspended on cables which pass over guiding-sheaves 31 and have their opposite ends made fast, as at 32. I carry these cables beneath sheaves 33, which are mounted on short arms 34, projecting from the hub of the guide-arms 35, which have loops or eyes 35^a, adapted to slide on the guide-rods 36. The hub 37 is secured with the shaft-section 8 by means of a set-screw 38 or other conven-

ient device, and these guides therefore serve 60 not only to steady the shaft in its movements, but they also prevent its rotation.

In Fig. 8 I have shown a bearing for the upper driving-gear 39. This gear is splined on the shaft 9, and its hub rests in the bush 65 40, which is also splined, on the shaft 9. 41 is a bearing-block, which rests on the top of the tub, and the lower face of the flange of the bush and the upper face of the bearing-block are grooved to form a race or way for 70 the balls 42. This construction obviates much friction in the driving-gear, requires no oiling, and permits the vertical adjustment of the shaft.

I claim—

75 1. In means for adjusting the mash-working devices of brewers' mashing-machines, the combination of a vertically-movable shaft constructed in two sections, the upper one of which is rotatable upon the lower and carries 80 the mash-working devices, said lower section being hollow and secured against rotation, and an adjusting-screw having a threaded engagement with the lower section and adapted to project into the hollow thereof in adjusting 85 the shaft, substantially as described.

2. In means for elevating the central shaft of brewers' mashing-machines, the combination, with the central shaft, of a screw for raising it, a driving-gear for turning the screw, 90 a support and ball-bearings for the hub of the driving-gear, and a divided coupling engaged with the support and the hub of the driving-gear for maintaining them in alignment, substantially as described.

95 3. In means for elevating the mash-working devices of brewers' mashing-machines, the combination, with the central shaft, of a screw for raising it, a driving-gear for turning the screw, a support and ball-bearings for 100 the hub of the driving-gear and a divided coupling engaged with the support and driving-gear, a driving-shaft having a pinion emmeshed with the driving-gear, and a bearing for the inner end of said shaft connected with 105 the coupling, whereby the shaft may be adjusted radially, substantially as described.

4. In means for adjusting the central shaft of brewers' mashing-machines, the combination, with a counterbalance, of guide-arms secured with the shaft and having studs carrying sheaves, over which the counterbalance-cables are carried, substantially as described.

CHARLES KAESTNER.
